E. A. ROBINSON

SLEEVE TERMINAL FOR TRAIN PIPES IN CONNECTER HEADS

Original Filed Jan. 7, 1922

UNITED STATES PATENT OFFICE.

EDWARD ARTHUR ROBINSON, OF MONTREAL, QUEBEC, CANADA, ASSIGNOR OF ONE-HALF TO HIMSELF AND ONE-HALF TO ELLISON EDWARD WORKMAN, OF MONTREAL, CANADA.

SLEEVE TERMINAL FOR TRAIN PIPES IN CONNECTER HEADS.

Original application filed January 7, 1922, Serial No. 527,568. Divided and this application filed April 5, 1924. Serial No. 704,531.

To all whom it may concern:

Be it known that I, EDWARD A. ROBINSON, a citizen of the United States, residing at Montreal, in the Province of Quebec and Dominion of Canada, have invented certain new and useful Sleeve Terminals for Train Pipes in Connector Heads, of which the following is a specification.

My invention relates to pipes intended to be seated in the heads of automatic connectors, forming terminals of train pipes and intended for automatic coupling to corresponding pipes upon adjoining cars to form a through connection.

This application is a division of my pending application Serial No. 527,568, filed January 7, 1922, for terminal sleeves for train pipes in connector heads.

The purpose of my invention is to make the train pipe terminals within the heads removable from the heads for replacement of gaskets while the heads are connected and the cars are coupled.

A further purpose is to form a long connection between the head and a removable abutment of the spring, pressing the train pipe terminal forward with respect to the head, so that the abutment can be backed off to withdraw the terminal and the parts may be replaced while the cars are coupled and the hose is connected with the train pipe terminal.

A further purpose is to enclose the spring forcing the train pipe terminal forward in the connector head within a removable and adjustable casing carrying an abutment for said spring so as to attain additional axial length of threaded connection between the parts without excessive thickness of head.

A further purpose is to provide the head with a removable front engaging surface surrounding the train pipe terminal and determining the effective "face" of the head at this point.

A further purpose is to make the engagement of separate parts of the head with the meeting parts of mating heads, in the posi-

tions corresponding to the individual train pipe terminals, adjustable not only when the heads are disconnected but even when the heads are connected by reason of coupling of the cars.

Further purposes will appear in the specification and in the claims.

Figure 1 is a side elevation showing one form of connector head and mounting therefor to which my invention is applicable.

Figure 2 is a broken longitudinal section through the head showing my invention applied thereto.

Figure 3 is a broken longitudinal section showing two opposed train pipe terminals and their correlated parts with the abutments in retracted position, preliminary to removal or ready for tightening after replacement of the gaskets.

Figures 4 and 5 are sections corresponding to Figure 3 and show slightly modified forms.

In all figures similar numerals indicate like parts.

In order to illustrate that my invention is used with connector heads that are normally mounted resiliently from brackets to relatively fixed train parts, I have shown one form of such head and mounting, but recognize that the particular form of such head and mounting does not affect the present invention except as the shape of the head or the location of the connections with respect to it may affect the use or accessibility of parts of my invention.

I describe the general structure of Figure 1, therefore, without here claiming this structure and for my purpose in this application view it as a generic mount which, however, is described and claimed in an application filed by me for terminal sleeves for train pipe in connector heads, Ser. No. 527,568, filed Jan. 7, 1922. I show a bracket 10 having at its lower end a threaded split clamp 11 tightened by bolt 12 about a helical spring 13 which is gripped within the threads of the clamp. This spring 13 is correspondingly threaded into and gripped by a

split clamp 14 tightened by bolt 15 embracing the outer end of the spring.

The split clamp 14 forms part of a support, here shown as of yoke form, and comprising arms 16 and 17 terminated at different heights, staggered laterally to lie on opposite sides of the head 18 and bolted to it at 19. The ends of the yoke arms abut against flanges 20 upon the rear of the head 10 so as to relieve the bolts from shearing thrust. The head is provided with the usual ears 21, staggered to cooperate with the corresponding ears and head of a mating connector.

15 The head 18 may be of any shape to suit the needs or whim of the designer. I have shown it in convenient form, as comprising three generally cylindrical train pipe bosses or body portions 22, 23 and 24 connected by 20 webs 25 and 26. In addition the body portions 22 and 23 are connected at the side by a fin 27 supporting one of the ears and the body portions 23 and 24 are connected on the opposite side by a fin 28 supporting the 25 other ear. The webs 25 and 26 on the opposite sides from the ears carry slight lateral flanges 20 which pass the thrust of the head to the yoke arms 16 and 17.

The body portions are shown as three in 30 number in the illustration because this corresponds with the maximum number of train pipes to be connected in actual service, normally three being used for passenger service and one or two for freight service. Obviously my invention is applicable to either 35 of the other types of service by reducing the number of body portions but without requiring any change in the constructions by which the gaskets may be replaced in 40 service without uncoupling.

Each body portion is cylindrically bored at 29 to receive the terminal tube 30.

This tube is removable and replaceable from the rear of the head. At its front end 45 it carries a gasket 31 and it and the gasket both preferably project beyond the face of the head.

The tube is enlarged at 32 to form a shoulder 33 and is threaded at the rear end 50 at 34 for attachment of a fitting by which connection to the air hose is made. Of course direct attachment of the air hose to the rear of the terminal is permissible.

The terminal is surrounded by a spring 35 and the bore in the head is threaded at 36. The spring rests against the inwardly extending shoulder 37 in a collar 38 which is threaded into the head and which in this 40 form passes through the head and preferably projects slightly beyond it in adjusted position so that the end of this collar may be used to take the wear and may be set forward to adjust for wear or to take care of any lack of alignment in the front face 45 of the head by projecting one or more col-

lars through further than the other collars or collar.

The collar is extended through at the rear so that a stop may be mounted upon it. This stop is shown as rigid, an integral 70 flange, 41' in the form in Figure 4, where its "lock nut" and stop values are desired but adjustment is not intended, but is shown as adjustable in other figures. In the latter figures the sleeve thread 40 is extended 75 rearwardly and upon it is mounted a nut 41 which is quite effective as a lock nut.

In both forms the extent of maximum projection of the terminal within the collar is limited by a stop, here shown as a pair of 80 nuts 42 mutually locking each other, and mounted upon the thread at the rear end of the terminal.

The fittings 43, 43' upon the rear of the terminals are intended to carry any suitable 85 connecting devices by which air and steam connection respectively may be made from the train pipes.

The interiors of the tubes carry spanner lugs 30' so that the terminals may be held 90 from the front end against rotation or may be turned from the front end to apply the fittings or for other purposes.

The springs press the tubes forward with 95 respect to the collars to an extent adjustably determined by the position of the tube stop.

The collar, forwardly counterbored to receive and surround the spring and externally threaded into the head, has sliding fit with the tube and has relatively long 100 threaded connection into the head so as to afford firm strong connection with the head and adaptation for threaded adjustment in the head to give varying spring compressions for the same gasket position. It is extended through the head to advantage, as illustrated in Figures 2 and 3. Any desired portion or all of the length of the collar may be externally threaded.

The collar is provided at its rear end with 110 a grip for a wrench or spanner and a polygonal wrench hold is shown at 44, smaller than the threaded exterior of the collar.

The stop limiting the forward position of the collar in the head may be adjustable 115 along the collar, as illustrated in Figures 2, 3 and 4, or nonadjustable. When adjustable (to permit adjusting spring compression without change in forward position of the gasket by corresponding adjustment of the tube stop) it may comprise merely a lock nut as indicated in Figures 2, 3 and 4.

The thread upon the end of the tube is tapered, corresponding to pipe thread, to receive the fitting. At some point 45 120 slightly beyond the fitting, the pipe thread leads into a thread of the same pitch and contour but of uniform depth and diameter, corresponding to a machine thread. The machine thread provides for a full thread 125 130

engagement of the nuts in any position along it while the pipe thread receives and tightens against the threads of the fitting. The positions of the lock nuts along the 5 length of the terminal tube determine the extent of normal projection of the terminal beyond the head when no mating head is engaged.

In assemblage, the spring, collar and lock 10 nuts are successively placed upon the terminal tube; the fitting is then connected and the tube assembly is ready for insertion in the head. Sufficient clearance is provided between the fitting and the normal 15 position of the tube stop to permit the lock nuts comprising the stop to be backed, preferably far enough to free the spring 34 wholly from compression.

The collar is now screwed to its position 20 after which the lock nuts are screwed forward and locked to adjust the projection of the gasket beyond the face. The adjustability of the collar within the head permits the position of the collar to be changed if the 25 desired spring compression does not coincide with the intended amount of projection beyond the front of the head.

In the main form the collar extends 30 through the head and the front of the collar becomes effective as the engaging portion of the head which meets the corresponding portion of the mating head; so that in case of wear this collar can be turned to vary the part receiving the wear, or can 35 be adjusted to give or to maintain the desired extent of projection.

By reason of the independent adjustability of the casings formed by these projecting collars surrounding the individual 40 train pipe terminals, these points of engagement with adjoining connector parts can be set up independently to correct any lack of alignment of the heads. They can be set up to obtain contact and some pressure even 45 when the cars are coupled, though the pressure present at this time would make it difficult to project them to what might be the preferred positions.

It will be evident that various changes 50 may be made by others interested in obtaining part or all of the advantage of my invention without copying it, and it is my purpose to include herein all such changes as come within the reasonable 55 spirit and scope of my invention.

Having thus described my invention, what I claim as new and desire to secure by Letters Patent is:—

1. In an automatic train pipe connector, a 60 connector head, having a bore through the head, a collar threaded into the head bore and extending beyond the bore to abut against another head and a train pipe terminal carried by said collar.

2. In an automatic train pipe connector, a 65

connector head having a bore through the head, a sleeve extending through the head and threaded into the bore, a train pipe terminal in the said sleeve and a gasket for said terminal adapted to engage a gasket of a 70 cooperating car.

3. In a train pipe connector, a head having a bore through the head, a sleeve extending through the head and threaded into the bore, a spring pressed train pipe terminal 75 carried by said sleeve normally extending beyond the sleeve to engage another terminal and a stop for limiting the forward movement of the terminal.

4. In an automatic train pipe connector, a 80 connector head having a bore therethrough, threads within the bore, a collar threaded into the bore and extending substantially therethrough, means for limiting the extension of said collar, an inwardly directed 85 abutment carried by said collar, a train pipe terminal movable within said collar and having an enlargement providing a rearwardly facing shoulder, a gasket carried by the terminal, a spring surrounding the terminal and engaging the shoulder and abutment and means carried by the terminal for limiting the forward movement of the terminal 90 within the collar.

5. In an automatic train pipe connector, a 95 connector head having a bore therethrough, threads within the bore, a collar threaded into the bore and extending substantially therethrough, means for adjustably limiting the extension of said collar to determine the 100 projection of the collar with respect to the head, an inwardly directed abutment carried by said collar, a train pipe terminal movable within said collar and having an enlargement providing a rearwardly facing shoulder, a gasket carried by the terminal, a spring surrounding the terminal and engaging the shoulder and abutment and means carried by the terminal for limiting the forward movement of the terminal 105 within the collar.

6. In a train pipe connector, a head having an opening therethrough, a tubular train pipe terminal in the opening, a rearwardly facing abutment on the terminal, a spring 115 surrounding the terminal and engaging the abutment, a sleeve surrounding the terminal, passing through the head and threaded thereinto, a stop upon the terminal and a lock nut for fixing the position of the said 120 sleeve in the head.

7. In a train pipe connector, a head having an opening therethrough, a tubular train pipe terminal in the opening, a rearwardly facing abutment on the terminal, a spring 125 surrounding the terminal and engaging the abutment, a sleeve surrounding the terminal, passing through the head and threaded thereinto, a stop upon the terminal and a locking device operating between the head 130

22
and the rear of the sleeve adapted to secure said sleeve against rotation in different adjusted positions.

8. In a train pipe connector, a head having a threaded bore of uniform diameter, a sleeve threaded into the head and extended therethrough, a train pipe terminal within the sleeve, a spring surrounding the termi-

nal, within the sleeve and engaging both sleeve and terminal axially of the latter, a stop upon the terminal engaging the sleeve and a fitting upon said terminal spaced from the stop to permit movement of the stop while the connection remains undisturbed. 10

EDWARD ARTHUR ROBINSON.
